UNITED STATES PATENT OFFICE

140,911

DESIGN FOR A SPOON OR OTHER ARTICLE OF FLATWARE

Philip Katz, Riverside, Calif.

Application February 26, 1945, Serial No. 118,155

Term of patent 14 years

(Cl. D54—12)

To all whom it may concern:

Be it known that I, Philip Katz, a citizen of the United States, residing at Riverside, in the county of Riverside and State of California, have invented a new, original, and ornamental Design for a Spoon or Other Article of Flatware, of which the following is a specification, reference being had therein to the accompanying drawing, forming a part thereof, in which

Figure 1 is an elevated front view of a spoon or other article of flatware, showing my new design, while

I claim:

The ornamental design for a spoon or other article of flatware, as shown.

PHILIP KATZ.
